UNITED STATES PATENT OFFICE.

GEORGE B. CANNON, JR., OF BROOKLYN, AND FRANK W. HOWARD, OF MOUNT VERNON,
NEW YORK.

WATERPROOF PAPER UMBRELLA.

Application filed March 25, 1922. Serial No. 546,864.

To all whom it may concern:

Be it known that we, GEORGE B. CANNON, Jr., and FRANK W. HOWARD, citizens of the United States, residing at Brooklyn, in the 5 county of Kings, and at Mount Vernon, in the county of Westchester, respectively, and State of New York, have invented new and useful Improvements in Waterproof Paper Umbrellas, of which the following is a specification.

This invention relates to umbrellas, and while features of the invention may be applicable to umbrellas having cloth covers, the invention is most useful when applied to 15 the construction of inexpensive paper umbrellas.

The general object of the invention is to produce an umbrella of this type having a cover which can be readily attached to the 20 frame, and in which the frame and cover are constructed in such a way as to reduce the strains and prevent the cover from being torn from the frame by the wind.

Further objects of the invention will appear hereinafter.

The invention consists in the novel features, and in the general combination of parts to be particularly described hereinafter, all of which contribute to produce a 30 simple and efficient water-proof paper umbrella.

A preferred embodiment of the invention will be particularly described in the following specification, while the broad scope of 35 the invention will be pointed out in the appended claims.

In the drawing,

Figure 1 is a vertical section through an umbrella embodying the invention;

40 Figure 2 is a plan showing a portion of the cover and particularly illustrating the general method of securing the same to the outer portion of the rib;

Figure 3 is also a plan showing a portion 45 of the edge of the cover before it is folded to form a hem;

Figure 4 is a section taken at the end of a rib and further illustrating details of the construction;

50 Figure 5 is a cross section taken through the cover of the umbrella at the point of connection of the umbrella sections and illustrating the details of this connection;

Figure 6 is a plan showing a portion of the 55 inner side of the cover and showing a modi-

fied construction for the opening in a sleeve which encases the outer portion of the rib;

Figure 7 is a cross section through these parts taken on the line 7—7 of Figure 6;

Figure 8 is a view similar to Figure 2 but 60 showing the preferred embodiment of the invention as to the details of construction at the end of the rib;

Figure 9 is a cross section taken on the line 9—9 of Figure 8;

Figure 10 is a view showing a portion 65 of two connected sections of the cover and particularly illustrating the means of working the reinforcing strip into the necessary shape in the vicinity of the umbrella crown; 70 and

Figure 11 is a perspective showing the portion of this strip at the fold where the direction of the strip must change near the 75 crown.

In practicing our invention we provide a frame very similar to an ordinary umbrella frame, that is to say, it comprises a stick 1, and ribs 2 which radiate from the umbrella crown 3. The ribs 2, however, are not 80 hinged to the crown, but have flattened ends as illustrated in Patent No. 1,229,271, which are clamped by the crown against the side of the stick and are flexed when the ribs are extended by means of the stretchers 4 which 85 are attached to a runner 5 on the stick. The umbrella cover 6 is composed of a plurality of sections 7, 7, etc., corresponding to the spaces between the ribs.

In applying the invention, sleeves 8 are 90 provided which are attached to the inner side of the cover and extend inwardly from the outer edge of the cover. These sleeves preferably extend all the way up to a point at the crown, but near the eyes 9 to which 95 the stretchers 4 are attached, these sleeves are provided with openings 11, respectively which permit the outer end of the ribs to be inserted and slid outwardly, in attaching the umbrella cover.

Figure 5 illustrated the simplest construction for the sleeve, and for attaching the same to the adjacent umbrella sections. The two adjacent umbrella sections are simply held with their adjacent edges together and the side edges of a strip of paper are then sewed completely through the same by means of stitches 10. In this way, one row of stitches operates to form the sleeve and secure the two adjacent cover sections together. 110

While the connection between the ribs and the stick has been referred to above as being the same as that shown in Patent No. 1,229,-271, it should be understood that any known 5 means or method may be employed for the umbrella construction at the crown. The invention disclosed herein relates especially to the means for connecting the ribs to the umbrella cover and for reinforcing the cover 10 where it comes against the ribs.

In Figure 5 it should be understood that this view shows the relation of the parts in an unnatural position simply to show the construction more intelligibly. As a matter 15 of fact, in the complete umbrella the sleeve lies flat against the inner side of the cover. Near the location of the stretcher eye 9 of each rib, the corresponding sleeve is provided with an opening or inclined slot 11 20 (see Figure 2) and at these slots the material of the sleeve is preferably reinforced by a short reinforcing strip 12 (see Figure 2). The ends of the umbrella ribs are provided with means to prevent them from injuring the cover in any way. This is preferably accomplished by providing enlargements or enlarged heads 13 on the ends of the ribs. This head may be formed simply 25 by bending the end of the rib into a closed eye. It is important that these eyes should be completely closed because otherwise they tend to become caught in other parts and interfere with the manufacturing of the umbrella. In order to strengthen the outer 30 edge of the umbrella cover a string or cord 14 is laid along this edge (see Figure 3) and the edge is then turned over so as to form a hem 15 attached by stitches 16 to the body of the cover. The ends of this cord 35 are attached together so that it operates to resist any force tending to enlarge the diameter of the umbrella at this point. Instead of having a diagonal slit 11 as shown in Figure 2, an opening 17 may be provided 40 (see Figure 6). This opening is of oval shape and is such as would be formed by punching out a small area of the material. In this case also the material of the sleeve is preferably reinforced by a reinforcing 45 piece 18. In assembling the umbrella the enlarged head or eye is inserted through the slit and shoved outwardly down the sleeve, the head or eye 13 being smooth and round 50 facilitates the thrusting of the rib through the sleeve without injuring the paper, and after the rib is in place this head also tends 55 to prevent the end of the rib from puncturing the paper near the edge of the cover.

The upper portion of the sleeve 8 lies between the rib and the cover and tends to distribute the pressure of the rib against the cover, thereby increasing the strength and durability of the umbrella at this point.

The eye on the end of the rib is preferably 60 formed in substantially the same plane as

the axis of the umbrella stick (see Figures 8 and 9), that is to say, the plane in which the eye is formed lies substantially at right angles to the cover. After the rib has been slid down into place the projecting end portion 19 of the sleeve is then folded around so as to lie over the eye or head 20. This folded over end can then be secured to the eye by any suitable means, for example, by means of a small wire staple 21 which may 75 be shoved through it and against the eye. The curved sides of the eye operate to turn the points of the staples as they come against them. The adjacent portion of the sleeve is preferably provided with a reinforcing 80 piece 22. These reinforcing pieces may be made of stiff paper or stout woven tape.

In view of the fact that the upper portions of the sleeves should always hold themselves between the rib and the cover, the openings 85 11 and 15 will be sufficiently short to insure that this would take place.

Where the cover sections 7 are attached together near the crown 3 of the umbrella they are cut so as to produce a projection or nave 90 23 in the cover adjacent to the crown. In order to produce this effect the adjacent edges of the umbrella sections are cut in a curve (see Figure 10). It is not feasible 95 to bend the paper strip 8 readily along a curved line and in order to enable the strip to adapt itself to this general shape we provide it with one or more folds 8^a having the general character illustrated in Figure 11. That is to say, the bifurcated or creased 100 strip is buckled into itself so as to form a transverse double fold. By having this fold wider on one side than the other the direction of the strip will be changed to make it conform to the general direction of the attached edges of the sections. See Fig. 10. These folds, however, do not interfere in any way with the sewing of the stitches 10 105 on a sewing machine, and have the effect of a reinforcement at this point.

It is understood that the embodiment of the invention described herein is only one of the many embodiments our invention may take, and we do not wish to be limited in the practice of our invention nor in our 115 claims, to the particular embodiment set forth.

What we claim is:

1. In an umbrella, the combination of a 120 stick, a crown carried thereby, a plurality of ribs secured to the stick at said crown, stretchers for holding the ribs extended, a cover attached to the stick at the crown and supported by said ribs, sleeves attached to the inner side of said cover extending inwardly from the outer edge of the cover, 125 said sleeves each having an opening to enable the ribs to be inserted in their corresponding sleeves and slid outwardly toward the outer edge of the cover.

2. In an umbrella, the combination of a stick, a crown carried thereby, a plurality of ribs secured to the stick at said crown, stretchers for holding the ribs extended, a cover attached to the stick at the crown and supported by said ribs, sleeves attached to the inner side of said cover extending inwardly from the outer edge of the cover, said sleeves each having an opening to enable the ribs to be inserted in their corresponding sleeves and slid outwardly toward the outer edge of the cover, said ribs having enlargements at their outer ends to prevent the same from injuring the cover.
3. In an umbrella, the combination of a stick, a crown carried thereby, a plurality of ribs secured to the stick at said crown, stretchers for holding the ribs extended, a cover attached to the stick at the crown and supported by said ribs, said cover having a hem turned about the outer edge thereof, sleeves attached to the inner side of the cover extending inwardly from a point near the hem and each having an opening to enable the ribs to be inserted in their corresponding sleeves and slid outwardly toward the outer edge of the cover, said ribs each having an integral enlarged head formed at the outer end thereof to prevent the same from injuring the cover.
4. In an umbrella, the combination of a stick, a crown carried thereby, a plurality of ribs secured to the stick at said crown, stretchers for holding the ribs extended, a cover attached to the stick at the crown and supported by said ribs, sleeves attached to the inner side of the cover extending inwardly from the outer edge of the cover to the crown, said sleeves each having an opening near the outer end of the adjacent stretcher to enable the ribs to be inserted in their corresponding sleeves and slid outwardly toward the outer edge of the cover.
5. In an umbrella, the combination of a stick, a crown carried thereby, a plurality of ribs secured to the stick at said crown, stretchers for holding the ribs extended, a cover attached to the stick at the crown and supported by said ribs, sleeves attached to the inner side of the cover extending inwardly from the outer edge of the cover to the crown, said sleeves each having an opening near the outer end of the adjacent stretcher to enable the ribs to be inserted in their corresponding sleeves and slid outwardly toward the outer edge of the cover, said ribs having integral eyes formed at the outer ends thereof to prevent injuring the cover, said sleeves having reinforcements at the outer ends thereof surrounding the outer end of the rib.
6. In an umbrella, the combination of a frame having a plurality of ribs, a cover composed of sections corresponding to the spaces between the ribs, sleeves attached to the adjacent edges of the cover sections and extending longitudinally with the ribs, the outer ends of said ribs lying within said sleeves, and the inner portions of said sleeves lying on the inner side of the cover and receiving the pressure of the ribs against the cover.
7. In an umbrella, the combination of a frame having a plurality of ribs, a cover composed of sections corresponding to the spaces between the ribs, sleeves extending longitudinally with the ribs and attached to the adjacent edges of the cover sections, the outer end of each sleeve being folded back upon itself to reinforce the outer end of the sleeve, the outer portions of said sleeves receiving and encasing the ribs, each of said ribs having means at its end for preventing the same from injuring the cover.
8. In an umbrella, the combination of a frame having a stick, and a plurality of ribs, a cover composed of sections corresponding to the spaces between the ribs, sleeves extending longitudinally with the ribs and attached to the adjacent edges of the cover sections, the outer portions of said sleeves receiving and encasing the ribs, each of said ribs having an integral eye formed at its outer end for preventing the same from injuring the cover.
9. In an umbrella, the combination of a frame having a stick, and a plurality of ribs, a cover composed of sections corresponding to the spaces between the ribs, sleeves extending longitudinally with the ribs and attached to the adjacent edges of the cover sections, the outer portions of said sleeves receiving and encasing the ribs, each of said ribs having an enlarged head formed at its outer end for preventing the same from injuring the cover, and each of said sleeves having an end portion folded back and lying over the enlarged head of its corresponding rib.
10. In an umbrella, the combination of a frame having a stick, and a plurality of ribs, a cover composed of sections corresponding to the spaces between the ribs, sleeves extending longitudinally with the ribs and attached to the adjacent edges of the cover sections, the outer portions of said sleeve receiving and encasing the ribs, each of said ribs having an enlarged head formed at its outer end for preventing the same from injuring the cover, and each of said sleeves having an end portion folded back and lying over the enlarged head of its corresponding rib, and means for securing the said folded end portion of the sleeve to the end of the rib.
11. In an umbrella, the combination of a frame having a stick, and a plurality of ribs, a cover composed of sections corresponding to the spaces between the ribs, sleeves ex-

tending longitudinally with the ribs and attached to the adjacent edges of the cover sections, the outer portions of said sleeves receiving and encasing the ribs, each of said 5 ribs having an enlarged head formed at its outer end for preventing the same from injuring the cover, and each of said sleeves having an end portion folded back and lying over the enlarged head of its corresponding 10 rib, and a reinforcing member secured within the outer portion of the sleeve at the end of the rib.

12. In an umbrella, the combination of a frame having a plurality of ribs, a cover 15 composed of sections corresponding to the spaces between the ribs, strips extending longitudinally with the adjacent edges of the cover sections, stitches passing through the adjacent edges of the cover sections and 20 through the edges of the strip, each of said strips constituting a sleeve extending longi-

tudinally with the rib, the outer ends of the ribs lying within the sleeves, and the outer end of each rib having an enlargement thereon to prevent the same from injuring the 25 umbrella cover.

13. In an umbrella, a paper cover composed of a plurality of substantially triangular sections connected together along their adjacent edges so as to produce an upward 30 projection of the cover at the crown and a reinforcing strip attached to the adjacent edges of the sections and folded upon itself adjacent to the crown to change the direction of the strip and enable the same to conform 35 to the shape of the projecting portion of the cover at the crown.

In testimony whereof, we have hereunto set our hands.

GEORGE B. CANNON, JR.
FRANK W. HOWARD.
